Section 1, Public Law 690, August 8, 1946
Patent expires February 7, 1967

12 Claims. (Cl. 70—366)

1

This invention relates to an improvement in cylinder locks of a known type, whereby the safety of the lock is considerably increased and a methodical picking of the lock is thus rendered substantially impossible.

The known type of cylinder locks comprises tumblers in the form of circular disks rotatably inserted in a lock barrel which in turn is rotatably inserted in a cylindrical bore in the casing. The barrel has a longitudinal slot in which a radially movable tumbler bar is disposed, which bar is received, in locking position, in a longitudinal locking groove in the casing and thus prevents rotation of the barrel in said casing. Each disk has a recess in its periphery and by means of a key that is introduced into a central key hole passing through all disks, they can be rotated into a position in which their recesses are aligned and form a continuous opening groove for partly receiving the tumbler bar which is thereby released from the casing and instead locks together the barrel with all disks so that the barrel and the disks may be rotated for opening of the lock. The radial parallel displacement of the tumbler bar is caused by a tangential force by means of a wedging action between the wedge surfaces of the bar and the locking groove and the disk recesses.

Locks of this type may be picked by causing a tangential force to act upon the barrel, so that the tumbler bar is pressed by said wedging action against the periphery of the disks, whereafter the disks are rotated one at a time by means of a suitable tool until it can be felt that the friction against the bar ceases and the recess of the disk thus registers with the bar.

The principal object of the invention is to provide a lock of the kind referred to, which comprises a plurality of tumbler bars and corresponding locking grooves and opening recesses and in which only one tumbler bar at a time can be brought into bearing contact with the tumbler disks when the lock is locked, whereby picking of the lock in the indicated manner is prevented.

Another object of the invention is to construct a lock of the kind referred to, comprising more than one tumbler bar, in such a way that when a tumbler bar has been brought into opening position by picking, the tumbler disks are fixed in relation to each other and to the barrel so as not to be individually adjustable in relation to another tumbler bar.

A further object of the invention is to provide a lock having tumbler disks with blind recesses

5 of the same size and form as the opening recesses so that a tumbler bar can be brought by picking into opening position by being introduced into both opening and blind recesses without indicating which of the recesses are blind ones.

Still another object of the invention is to provide the different tumbler bars with positioning extensions fitting into corresponding recesses in connection with the locking grooves, so that each tumbler bar can be moved into a determined groove only.

A still further object of the invention is to provide means for holding the tumbler bars parallel to the axis of the barrel and for preventing longitudinal movement of the tumbler bars.

Further objects and advantages of the invention will appear from the following description of two embodiments of the invention, reference being had to the accompanying drawings in

20 which:

Fig. 1 is an axial section through the first embodiment of the invention, taken on line I—I in Fig. 3.

Fig. 2 is an axial section on line II—II in Fig. 3.

Fig. 3 is an end view, as seen from the left according to Figs. 1 and 2.

Figs. 4 and 5 are cross sections on line IV—IV in Fig. 1, showing the lock in locked and opened position, respectively.

Fig. 6 is a similar cross section of the lock in another locking position that may occur when it is tried to pick the lock.

Fig. 7 shows a detail in cross section on line VII—VII in Fig. 1.

Fig. 8 is a cross section similar to Fig. 7, but showing the parts in another position.

Figs. 9 and 10 show a modification partly in axial section along lines corresponding to lines I—IX and II—II in Fig. 3, respectively.

Fig. 11 shows a washer.

Fig. 12 shows a side view of the key of the lock.

Fig. 13 shows the key of the lock in cross section on line XIII—XIII in Fig. 12.

Figs. 14 and 15 show partly in axial sections corresponding to Figs. 1 and 2, another embodiment of the invention.

Fig. 16 shows a detail in cross section on line XVI—XVI in Fig. 14.

Fig. 17 is a cross section similar to Fig. 16, but showing the parts in another position.

Referring to the drawings, in the first embodiment shown in Figs. 1 to 13 the lock according to the invention comprises a casing 1 with a cylindrical bore which is completely open at the rear but is closed at its front end by means of an

end wall 2 having a centrally disposed, circular key hole 3. In the bore of the casing there is inserted from the rear a barrel 4 rotatable in the casing and closed at its rear end by means of an end wall 5 which on the outside has coupling means 6 for connection to the lock bolt (not shown) for manipulating it. The barrel is retained in the casing by a disk 7 which is attached by means of a screw 8 to the rear end of the casing and which is slotted at its one side so as to form a click spring 9 adapted to engage a notch 10 in the end wall of the barrel in order to stop the barrel in a certain position on turning it in locking direction. The disk 7 has a suitable hole 11 for the coupling means 6.

Alternating with washers 13 there is inserted in the barrel 4 a number of tumbler disks 12 (in the present case ten) rotatably fitting in the barrel. Said washers 13 being shown in Fig. 11, each comprise a projection 14 engaging a wide longitudinal slot 15 in the barrel 4, so that the disks cannot be rotated in relation to the barrel. Furthermore, the washers have a central hole 16 permitting the key pertaining to the lock freely to pass therethrough, and a recess 17 at their periphery for a purpose to be indicated in the following. The tumbler disks 12 are all provided with a central key hole in the form of a circle sector having a centre angle of preferably at least 180°. The radial edges of the key holes of the tumbler disks form abutments for the key when opening and closing the lock, respectively.

The key (Figs. 12 and 13) is in the form of a number of coaxial sectors 18 laid after each other and each forming abutments for a tumbler disk, and as all sectors have different centre angles the key when introduced into the closed lock and turned in opening direction, in the present case in clockwise direction, successively acts upon all tumbler disks causing them to occupy a determined position in relation to each other and to the other parts of the lock. In this position two sets of opening recesses a primary one 19 and a secondary one 20, provided in the tumbler disks are each brought into alignment with each other (Fig. 5), so as to form two continuous longitudinal opening grooves. The barrel 4 has two longitudinal slots 21 and 22 and the inside of the casing has two longitudinal locking grooves 23 and 24 at the same mutual angular spacing as the recesses 19 and 20 of the tumbler disks. In each of the slots 21 and 22 of the barrel there is placed a longitudinal tumbler bar 25 and 26, respectively, which is radially movable and of such a width as to be partly received, in locking position (Fig. 4), within the locking grooves of the casing, whereby said bar locks the barrel in the casing but leaves the tumbler disks free, and as to be partly received, in opening position (Fig. 5), within a corresponding opening groove formed by the opening recesses of the tumbler disks, whereby said bar locks the tumbler disks in the barrel but leaves the latter free in relation to the casing so that the lock may be opened.

The movement of the tumbler bars 25, 26, which is made possible thanks to the recesses 17 of the washers 13, is realized by tangential pressure from the barrel 4 or the tumbler disks 12. The locking grooves 23 and 24 of the casing as well as the recesses 19 and 20 of the tumbler disks each have one of their sides inclined in relation to the radius, and the tumbler bars have wedge surfaces at their corresponding sides, so as to co-operate when opening and closing the lock with the inclined sides like wedges. When opening the lock

the tumbler bars are thus pressed by the barrel against the inclined sides of the locking grooves of the casing and are thereby moved out of said grooves and into the opening recesses of the tumbler disks, while upon locking the inclined sides of the opening recesses of the tumbler disks press the tumbler bars outwardly into locking position in the locking grooves of the casing.

For rotation of the barrel 4 in the casing 1 at least one of the tumbler disks 12 comprises a pin 27 projecting from the periphery of the disk into the wide slot 15 of the barrel to act upon an edge of the slot after a certain rotation of the disk. The pin is disposed so as to strike the slot edge, upon opening, at the same moment as the opening recesses 19 and 20, respectively, of the tumbler disks are aligned with each other, so that upon continued turning of the key the barrel is released in the manner described above and the lock is opened.

Upon locking, when turning the key in the opposite direction, i. e. anti-clockwise in the present case, one or more tumbler disks are immediately caused to press the tumbler bars outwardly so that the latter as soon as they register with their respective locking grooves in the casing, fall into said grooves and lock the barrel, which takes place simultaneously with the click spring 9 engaging the notch 10 and stopping the barrel. In order that the key may be taken out it must be further turned, its locking abutment, consisting of a plane surface 28, collecting all tumbler disks one at a time and bringing their key holes to register, which takes place at the same time as the pin 27 strikes the edge of the slot 15 and thus prevents any continued turning.

The tumbler bars 25 and 26 are formed so as to be able only to fall into their proper locking grooves 23 and 24, respectively, in the casing 1. For this purpose they may be provided at either end or both ends with lateral extensions 29 and 30, respectively, projecting in opposite directions and fitting in corresponding recesses 31 in connection with the corresponding locking grooves, or the bars and also the locking grooves may be of different lengths, as shown in Fig. 10. In the latter case the shorter bar 25 is anchored, preferably by means of a radial pin 32, in a bore 33 in the barrel so as not to be displaceable longitudinally. Combinations of both arrangements may also be suitable.

In order to prevent the possibility of picking the lock in the manner indicated in the introduction, at least some of the tumbler disks 12 are each provided with one or more blind or misleading recesses 34 which may be of the same size and form as the opening recesses 19 and 20. Said blind recesses, of course, per se make the picking of the lock more difficult, but the invention furthermore comprises a new arrangement making the picking of the lock practically impossible and involving that, in locking position, the tumbler bars cannot be simultaneously pressed against the tumbler disks.

In the first embodiment of the invention this is realized simply by the fact that the locking grooves 23, 24 of the casing and the tumbler bars 25, 26 are so dimensioned in relation to each other that, in ordinary locking position (Fig. 4), only one bar 25 which is here called the primary bar, positively locks the barrel 4 in the casing 1, while the secondary bar 26 has a certain clearance in its groove 24. As a result thereof, the tumbler disks can each be adjusted, without the aid of the proper key, into opening position only in rela-

tion to the primary tumbler bar 25, since the secondary bar 26 cannot be caused to exert pressure on and thus friction against the tumbler disks. The primary bar 25 can, however, be brought into opening position, but then the situation shown in Fig. 6 arises, since it is almost absolutely certain that at least some of the recesses into which the bar falls, is a blind or possibly a secondary one and consequently the secondary tumbler bar has no continuous opening groove in the tumbler disks to fall into. It should be observed that only the proper opening recesses 19, 20 in each tumbler disk have the same mutual angular spacing as the slots 21, 22 of the barrel 4. In this situation the secondary tumbler bar 26 may be pressed against the tumbler disks, it is true, but now the latter are locked in relation to each other and the barrel and thus cannot be adjusted individually.

In the second embodiment shown in Figs. 14 to 17, the two tumbler bars 25b, 26b and their locking grooves 23, 24 may be of such dimensions that the two bars simultaneously positively lock the barrel 4 in the casing 1. However, the primary tumbler bar 25b here has an arm 35 which extends along the periphery of the barrel and always underlies the secondary tumbler bar 26b and in normal locking position holds the latter free from the tumbler disks, but when the primary tumbler bar 25b falls into opening position, said arm permits the secondary tumbler bar 26b also to fall into opening position. On the other hand, in opening position the secondary tumbler bar 26b holds the primary tumbler bar 25b pressed in, so that the latter cannot be moved out into locking position before the secondary bar. Thereby the primary bar 25b is prevented from falling into the wrong locking groove if the tumbler bars are placed in such relationship that on turning the barrel in locking direction the primary tumbler bar 25b must pass the secondary locking groove 24 before it reaches its proper locking groove 23. The arm 35 is provided at its free end with a pivot 36 parallel to the tumbler bar and rotatably mounted in the barrel, said pivot forming a fulcrum for the tumbler bar 25b in its movements and holding it correctly positioned. The secondary tumbler bar 26b is preferably in a similar manner pivotally mounted and guided in the barrel by means of a transverse arm 37 and a pivot 38.

The invention is not limited to the embodiments thereof described above and shown in the drawings, for said embodiments may be modified in different ways without departing from the scope of the appended claims. Thus, the tumbler disks may be of any suitable number, and the lock may be provided, if desired, with three or more tumbler bars with pertaining recesses, slots and grooves, whereby the safety of the lock is further increased.

What I claim and desire to secure by Letters Patent is:

1. A cylinder lock operable by a key, comprising a casing having a cylinder bore and a plurality of longitudinal locking grooves in its inner wall, a lock barrel in said bore having longitudinal slots corresponding to said locking grooves, a plurality of circular tumbler disks independently rotatable in said barrel and having opening recesses at their edges corresponding to said locking grooves and said slots and adapted to be aligned for forming continuous opening grooves on rotating said disks by said key for opening the lock, said disks also having blind

recesses, a radially movable, longitudinal tumbler bar having wedge shaped surfaces thereon in each of said barrel slots, each of said tumbler bars in locking position being partly received in a corresponding one of said locking grooves to prevent rotation of said barrel in relation to said casing and in opening position being partly received in a corresponding one of said opening grooves for releasing said barrel in relation to said casing and locking said tumbler disks in relation to each other and to said barrel, said locking grooves and said longitudinal slots each having one side thereof inclined with respect to the radius of the lock and together with the wedge shaped surfaces of said tumbler bars forming wedge means for forcing said tumbler bars radially inwards and outwards by said barrel or said disks being actuated by the key, and supporting means coacting with said tumbler bars for preventing one of said tumbler bars from being forced by said wedge means against said tumbler disks when another of said tumbler bars is in its locking position.

2. A cylinder lock operable by a key, comprising a casing having a cylinder bore and a plurality of longitudinal locking grooves in its inner wall, a lock barrel in said bore having longitudinal slots corresponding to said locking grooves, a plurality of circular tumbler disks independently rotatable in said barrel and having opening recesses at their edges corresponding to said locking grooves and said slots and adapted to be aligned for forming continuous opening grooves on rotating said disks by said key for opening the lock, said disks also having blind recesses, a radially movable, longitudinal tumbler bar having wedge shaped surfaces thereon in each of said barrel slots, each of said tumbler bars in locking positions being partly received in a corresponding one of said locking grooves to prevent rotation of said barrel in relation to said casing and in opening position being partly received in a corresponding one of said opening grooves for releasing said barrel in relation to said casing and locking said tumbler disks in relation to each other and to said barrel, positioning means including extensions on said tumbler bars, said locking grooves having corresponding recesses therein, said positioning means being adapted to be received in said corresponding recesses in said locking grooves, so that each of said tumbler bars can be partly received only in its corresponding locking grooves, said locking grooves and said longitudinal slots each having one side thereof inclined with respect to the radius of the lock and together with the wedge shaped surfaces of said tumbler bars forming wedge means for forcing said tumbler bars radially inwards and outwards by said barrel or said disks being actuated by the key, and supporting means coacting with said tumbler bars for preventing one of said tumbler bars from being forced by said wedge means against said tumbler disks when another of said tumbler bars is in its locking position.

3. A cylinder lock operable by a key, comprising a casing having a cylinder bore and a primary longitudinal locking groove and a secondary longitudinal locking groove in its inner wall, a lock barrel in said bore having a primary longitudinal slot and a secondary longitudinal slot corresponding to said locking grooves, a plurality of circular tumbler disks independently rotatable in said barrel and each having a primary opening recess and a secondary open-

ing recess corresponding to said locking grooves and said slots and adapted to be aligned for forming two continuous opening grooves on rotating said disks by the proper key for opening the lock, the disks also having blind recesses, a primary tumbler bar in said primary barrel slot and a secondary tumbler bar in said secondary barrel slot, wedge means including wedge surfaces in said locking grooves and said tumbler disk recesses and on said tumbler bars for forcing said bars radially outwards into locking position, in which said barrel is locked in said casing, or radially inwards into opening position, in which said barrel is released from said casing and said tumbler disks are locked in relation to each other and to said barrel, said secondary locking groove being dimensioned to provide a clearance space between said wedge surfaces of said secondary locking groove and said secondary tumbler bar, so that said secondary bar can be forced inwards into engagement with said tumbler disks only when said primary tumbler bar is in opening position releasing said barrel and locking said tumbler disks.

4. A cylinder lock operable by a key, comprising a casing having a cylinder bore and a primary longitudinal locking groove and a secondary longitudinal locking groove in its inner wall, a lock barrel in said bore having a primary longitudinal slot and a secondary longitudinal slot corresponding to said locking grooves, a plurality of circular tumbler disks independently rotatable in said barrel and each having a primary opening recess and a secondary opening recess corresponding to said locking grooves and said slots and adapted to be aligned for forming two continuous opening grooves on rotating said disks by the proper key for opening the lock, the disks also having blind recesses, a primary tumbler bar in said primary barrel slot and a secondary tumbler bar in said secondary barrel slot, wedge means including wedge surfaces in said locking grooves and said tumbler disk recesses and on said tumbler bars for forcing said bars radially outwards into locking position, in which said barrel is locked in said casing, or radially inwards into opening position, in which said barrel is released from said casing and said tumbler disks are locked in relation to each other and to said barrel, said secondary locking groove being dimensioned to provide a clearance space between said wedge surfaces of said secondary locking groove and said secondary tumbler bar, so that said secondary bar can be forced inwards into engagement with said tumbler disks only when said primary tumbler bar is in opening position releasing said barrel and locking said tumbler disks, and guiding means for keeping said tumbler bars parallel with the axis of said barrel and preventing longitudinal movement of one of said tumbler bars including a radial pin on said one tumbler bar and a radial bore in said barrel, said pin being anchored in said radial bore in said barrel.

5. A cylinder lock operable by a key, comprising a casing having a cylinder bore and a primary longitudinal locking groove and a secondary longitudinal locking groove in its inner wall, a lock barrel in said bore having a primary longitudinal slot and a secondary longitudinal slot corresponding to said locking grooves, a plurality of circular tumbler disks independently rotatable in said barrel and each having a primary opening recess and a secondary opening recess corresponding to said locking grooves and said slots

and adapted to be aligned for forming two continuous opening grooves on rotating said disks by the proper key for opening the lock, the disks also having blind recesses, a primary tumbler bar in said primary barrel slot and a secondary tumbler bar in said secondary barrel slot, wedge means including wedge surfaces in said locking grooves and said tumbler disk recesses and on said tumbler bars for forcing said bars radially outwards into locking position, in which said barrel is locked in said casing, or radially inwards into opening position, in which said barrel is released from said casing and said tumbler disks are locked in relation to each other and to said barrel, and a lateral arm on said primary tumbler bar underlying said secondary tumbler bar and keeping it out of engagement with said tumbler disks when said primary tumbler bar is in locking position and preventing said primary tumbler bar from moving into locking position when said secondary tumbler bar is in opening position.

6. A cylinder lock operable by a key, comprising a casing having a cylinder bore and a primary longitudinal locking groove and a secondary longitudinal locking groove in its inner wall, a lock barrel in said bore having a primary longitudinal slot and a secondary longitudinal slot corresponding to said locking grooves, a plurality of circular tumbler disks independently rotatable in said barrel and each having a primary opening recess and a secondary opening recess corresponding to said locking grooves and said slots and adapted to be aligned for forming two continuous opening grooves on rotating said disks by the proper key for opening the lock, the disks also having blind recesses, a primary tumbler bar in said primary barrel slot and a secondary tumbler bar in said secondary barrel slot, wedge means including wedge surfaces in said locking grooves and said tumbler disk recesses and on said tumbler bars for forcing said bars radially outwards into locking position, in which said barrel is locked in said casing, or radially inwards into opening position, in which said barrel is released from said casing and said tumbler disks are locked in relation to each other and to said barrel, a lateral arm on said primary tumbler bar underlying said secondary tumbler bar and keeping it out of engagement with said tumbler disks when said primary tumbler bar is in locking position and preventing said primary tumbler bar from moving into locking position when said secondary tumbler bar is in opening position, a lateral arm on said secondary tumbler bar, and longitudinally extending pivots on said lateral arms rotatably mounted in longitudinal bores in said barrel to keep said tumbler bars parallel with the axis of said barrel and prevent longitudinal movement of said tumbler bars.

7. A cylinder lock operable by a key, comprising a casing having a cylinder bore and a plurality of longitudinal locking grooves in its inner wall and a cam surface forming one side of each locking groove, a lock barrel in said bore having longitudinal slots corresponding to said locking grooves, a plurality of tumbler disks independently rotatable in said barrel and having opening recesses so positioned at the edges of the disks as to be aligned for forming a continuous opening groove behind each of said barrel slots on rotating said disks by said key in opening direction and having one edge fashioned to form a cam surface in each opening groove, a radially movable longitudinal tumbler bar in

each of said barrel slots, which in locking position is partly received in a corresponding one of said locking grooves to prevent rotation of said barrel in relation to said casing and in opening position partly received in a corresponding one of said opening grooves for permitting rotation of said barrel in relation to said casing and preventing rotation of said tumbler disks in relation to each other and to said barrel, each tumbler bar having a cam surface for cooperation with said cam surfaces in said locking grooves and said opening grooves to force each tumbler bar into opening and locking position, respectively, on rotation of said disks in opening or closing direction, and supporting means for preventing one of said tumbler bars from being forced radially inward by said cam surfaces when another of said tumbler bars is in locking position.

8. A cylinder lock operable by a key, comprising a casing having a cylinder bore and a plurality of longitudinal locking grooves in its inner wall and a cam surface forming one side of each locking groove, a lock barrel in said bore having longitudinal slots corresponding to said locking grooves, a plurality of tumbler disks independently rotatable in said barrel and having opening recesses so positioned at the edges of the disks as to be aligned for forming a continuous opening groove behind each of said barrel slots on rotating said disks by said key in opening direction and having one edge fashioned to form a cam surface in each opening groove, a radially movable longitudinal tumbler bar in each of said barrel slots, which in locking position is partly received in a corresponding one of said locking grooves to prevent rotation of said barrel in relation to said casing and in opening position partly received in a corresponding one of said opening grooves for permitting rotation of said barrel in relation to said casing and preventing rotation of said tumbler disks in relation to each other and to said barrel, each tumbler bar having a cam surface for cooperation with said cam surfaces in said locking grooves and said opening grooves to force said tumbler bar into opening and locking position, respectively, on rotation of said disks in opening or closing direction, positioning means including extensions on said tumbler bars adapted to be received in corresponding recesses in connection with said locking grooves and permitting each of said tumbler bars to be partly received only in its corresponding locking groove, and supporting means for preventing one of said tumbler bars from being forced radially inwards by said cam surfaces when another of said tumbler bars is in locking position.

9. A cylinder lock operable by a key, comprising a casing having a cylinder bore and a primary longitudinal locking groove and a secondary longitudinal locking groove in its inner wall, and a cam surface forming one side of each locking groove, a lock barrel in said bore having a primary longitudinal slot and a secondary longitudinal slot corresponding to said locking grooves, a plurality of tumbler disks independently rotatable in said barrel and having each a primary and a secondary opening recess so positioned at the edges of the disks as to be aligned for forming a continuous opening groove behind each of said barrel slots on rotation of said disks by said key in opening direction and having one edge fashioned to form a cam surface in each opening groove, said disks also having blind re-

cesses, a primary and a secondary tumbler bar in said primary and secondary barrel slot, respectively, which in locking position are partly received in said primary and secondary locking groove, respectively, to prevent rotation of said barrel in relation to said casing and in opening position partly received in said primary and secondary opening groove, respectively, for permitting rotation of said barrel in relation to said casing and preventing rotation of said tumbler disks in relation to each other and to said barrel, each tumbler bar having a cam surface for cooperation with said cam surfaces in said locking grooves and said opening grooves to force each tumbler bar into opening and locking position, respectively, on rotation of said disks in opening or closing direction, said secondary tumbler bar being so dimensioned in relation to said secondary locking groove as to leave in locking position a clearance space between its cam surface and said cam surface in said locking groove, permitting said secondary tumbler bar to be forced into engagement with said tumbler disks only when said primary tumbler bar is in opening position releasing said barrel and locking said tumbler disks.

10. A cylinder lock operable by a key, comprising a casing having a cylinder bore and a primary longitudinal locking groove and a secondary longitudinal locking groove in its inner wall, and a cam surface forming one side of each locking groove, a lock barrel in said bore having a primary longitudinal slot and a secondary longitudinal slot corresponding to said locking grooves, a plurality of tumbler disks independently rotatable in said barrel and having each a primary and a secondary opening recess so positioned at the edges of the disks as to be aligned for forming a continuous opening groove behind each of said barrel slots on rotation of said disks by said key in opening direction and having one edge fashioned to form a cam surface in each opening groove, said disks also having blind recesses, a primary and a second tumbler bar in said primary and secondary barrel slot, respectively, which in locking position are partly received in said primary and secondary locking groove, respectively, to prevent rotation of said barrel in relation to said casing and in opening position partly received in said primary and secondary opening groove, respectively, for permitting rotation of said barrel in relation to said casing and preventing rotation of said tumbler disks in relation to each other and to said barrel, each tumbler bar having a cam surface for cooperation with said cam surfaces in said locking grooves and said opening grooves to force said tumbler bars into opening and locking position respectively, on rotation of said disks in opening or closing direction, said secondary tumbler bar being so dimensioned in relation to said secondary locking groove as to leave in locking position a clearance space between its cam surface and said cam surface in said locking groove, permitting said secondary tumbler bar to be forced into engagement with said tumbler disks only when said primary tumbler bar is in opening position releasing said barrel and locking said tumbler disks, and guiding means including a radial pin on each of said tumbler bars slidably mounted in corresponding radial bores in said barrel to keep said tumbler bars parallel with the axis of said barrel and prevent longitudinal movement of said tumbler bars.

11. A cylinder lock operable by a key, compris-

11

ing a casing having a cylinder bore and a primary longitudinal locking groove and a secondary longitudinal locking groove in its inner wall, and a cam surface forming one side of each locking groove, a lock barrel in said bore having a primary longitudinal slot and a secondary longitudinal slot corresponding to said locking grooves, a plurality of tumbler disks independently rotatable in said barrel and having each a primary and a secondary opening recess so positioned at the edges of the disks as to be aligned for forming a continuous opening groove behind each of said barrel slots on rotation of said disks by said key in opening direction and having one edge fashioned to form a cam surface in each opening groove, said disks also having blind recesses, a primary and a secondary tumbler bar in said primary and secondary barrel slot, respectively, which in locking position are partly received in said primary and secondary locking groove, respectively, to prevent rotation of said barrel in relation to said casing and in opening position partly received in said primary and secondary opening groove, respectively, for permitting rotation of said barrel in relation to said casing and preventing rotation of said tumbler disks in relation to each other and to said barrel, each tumbler bar having a cam surface for cooperation with said cam surfaces in said locking grooves and said opening grooves to force said tumbler bars into opening and locking position, respectively, on rotation of said disks in opening or closing direction, and a lateral arm on said primary tumbler bar underlying said secondary tumbler bar and keeping it out of engagement with said tumbler disks when said primary tumbler bar is in locking position and preventing said primary tumbler bar from moving into locking position when said secondary tumbler bar is in opening position.

12. A cylinder lock operable by a key, comprising a casing having a cylinder bore and a primary longitudinal locking groove and a secondary longitudinal locking groove in its inner wall, and a cam surface forming one side of each locking groove, a lock barrel in said bore having a primary longitudinal slot and a secondary longitudinal slot corresponding to said locking grooves,

12

a plurality of tumbler disks independently rotatable in said barrel and having each a primary and a secondary opening recess so positioned at the edges of the disks as to be aligned for forming a continuous opening groove behind each of said barrel slots on rotation of said disks by said key in opening direction and having one edge fashioned to form a cam surface in each opening groove, said disks also having blind recesses, a primary and a secondary tumbler bar in said primary and secondary barrel slot, respectively, which in locking position are partly received in said primary and secondary locking groove, respectively, to prevent rotation of said barrel in relation to said casing and in opening position partly received in said primary and secondary opening groove, respectively, for permitting rotation of said barrel in relation to said casing and preventing rotation of said tumbler disks in relation to each other and to said barrel, each tumbler bar having a cam surface for cooperation with said cam surfaces in said locking grooves and said opening grooves to force said tumbler bars into opening and locking position respectively, on rotation of said disks in opening or closing direction, a lateral arm on said primary tumbler bar underlying said secondary tumbler bar and keeping it out of engagement with said tumbler disks when said primary tumbler bar is in locking position and preventing said primary tumbler bar from moving into locking position when said secondary tumbler bar is in opening position, and a lateral arm on said secondary tumbler bar, and longitudinally extending pivots on said lateral arms mounted in longitudinal bores in said barrel to keep said tumbler bars parallel with the axis of said barrel and prevent longitudinal movement of said tumbler bars.
